US0D1060787S

(12) **United States Design Patent** (10) **Patent No.:** **US D1,060,787 S**
(45) **Date of Patent:** **** Feb. 4, 2025**

(54) **PORTABLE LAMP**

(71) Applicant: **SHENZHEN JYC
PHOTOELECTRICITY
TECHNOLOGY CO., LTD.**, Shenzhen
(CN)

(72) Inventor: **Huisheng Zou**, Shenzhen (CN)

(73) Assignee: **SHENZHEN JYC
PHOTOELECTRICITY
TECHNOLOGY CO., LTD.**, Shenzhen
(CN)

(**) Term: **15 Years**

(21) Appl. No.: **29/937,144**

(22) Filed: **Apr. 12, 2024**

(51) **LOC (15) Cl. 26-02**

(52) **U.S. Cl.**
USPC **D26/41**

(58) **Field of Classification Search**

USPC D26/37, 40, 41, 72, 113
CPC F21L 4/08; F21L 19/00; F21L 4/00; F21V
21/145; F21W 2111/10

(57) **CLAIM**

The ornamental design for a portable lamp as shown and described.

DESCRIPTION

FIG. 1 is a perspective view of a portable lamp showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is an enlarged view of portion 8 shown in FIG. 1. The portable lamp is shown with a symbolic break in its length and the appearance of any portion of the portable lamp between the break lines form no part of the claimed design. The dash-dash broken lines in the drawings depict portions of the portable lamp that form no part of the claimed design. The dot-dash broken lines in the drawings depict boundaries of the enlarged portion and form no part of the claimed design.

1 Claim, 8 Drawing Sheets
